OF D 15,855

DESIGN.

—o—
J. L. FOLSOM.

CARPET.

No. 15,855.

Patented Feb. 24, 1885.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 15,855, dated February 24, 1885.

Application filed January 14, 1885. Term of patent 3½ years.

To all whom it may concern:

Be it known that I, JAMES L. FOLSOM, of Brooklyn, New York, have invented a new and original Design for Carpets, of which the following is a specification, reference being had to the accompanying photograph, which forms a part of the same.

The invention relates to a design to be worked into or upon surfaces such as carpets or similar fabrics; and it consists in the novel configuration and grouping of figures herein specifically shown and claimed.

The accompanying photograph is a face view of a carpet showing my new design.

15 The design consists of four groups and disconnected small work in the intervening spaces.

20 The group A is shown at the upper part of the photograph. It consists of a thick central mass of oak leaves and open flowers on a dark ground, supported on scrolled border-work and surrounded with small geometric ornamentation, beyond which project leaf and fern sprays.

25 The group B is shown at the lower center of the photograph. It consists of a smaller flower and leaf cluster resting on a scrolled support and having fern and blossom sprays projecting outward.

30 The group C is shown at the right center and at the left upper and lower corners of the photograph. It also consists of a thick central mass of leaves and flowers resting on a

scrolled and ornamented support, and having a group of flag-like leaves and a blossom spray 35 above.

The group D is shown at the left center and at the right upper and lower corners of the photograph. It consists of a central mass of leaves having clusters of small star-shaped 40 flowers on the left and above, and resting on a smaller scrolled support. Above are projecting leaf and flower sprays, and on the right a blossom spray.

In various places these several groups approach each other, but do not interblend. The intervening spaces have here and there small disconnected skeleton leaves and geometric work.

I claim—

1. The design for a carpet, consisting of the group A, substantially as shown and described.
2. The design for a carpet, consisting of the group B, substantially as shown and described.
3. The design for a carpet, consisting of the group C, substantially as shown and described.
4. The design for a carpet, consisting of the group D, substantially as shown and described.
5. The design for a carpet, consisting of the groups A, B, C, and D, substantially as shown 55 and described.

J. L. FOLSOM.
